UNITED STATES PATENT OFFICE.

HARRY LYON, OF BROCKTON, MASSACHUSETTS, ASSIGNOR TO THOMAS BOSTOCK & SONS, OF BROCKTON, MASSACHUSETTS, A COPARTNERSHIP COMPOSED OF THOMAS BOSTOCK, GEORGE BOSTOCK, AND JAMES BOSTOCK.

LEATHER-SPLITTING MACHINE.

1,164,829.

Specification of Letters Patent. Patented Dec. 21, 1915.

Application filed December 15, 1914. Serial No. 877,309.

To all whom it may concern:

Be it known that I, HARRY LYON, a citizen of the United States, and resident of Brockton, in the county of Plymouth and State of Massachusetts, have invented certain new and useful Improvements in Leather-Splitting Machines, of which the following is a specification.

The present invention relates to machines for splitting leather, adapted to act on sheets or cut pieces of leather, such as soles, heel lifts, and other pieces, of any size within the limits of the machine, such machine being of the type in which the pieces to be split are fed against the edge of a splitting knife by means of feed rolls between which the leather pieces pass and by which the pieces are gripped.

The general object of the present invention is to provide a machine of the character indicated adapted to split leather evenly, whether the piece is wide or narrow, or hard or soft; and to secure accurate uniformity of thickness over all parts of a piece which may vary in width or in hardness, or in both width and hardness, at different points.

In order better to explain my object I will mention briefly a defect in the operation of the common form of splitting machine of the type indicated. In machines of this type usually one of the feed rolls is rigidly mounted and the other is yieldingly mounted and pressed toward the rigidly supported roll by means of springs stiff enough to apply the pressure necessary to force past the knife a piece of leather of the maximum width capable of being acted on by the machine. Just as great a pressure is applied by these springs to a narrow or a soft piece as to a wide or hard piece, with the result that pieces which vary in width, or in hardness, or in both width and hardness, are more or less crushed and condensed in the narrower and softer portions in passing between the rolls, and are delivered from the machine varying in thickness. This effect occurs because the unit pressure applied by the rolls to the piece varies in inverse proportion to the width of the piece, the full pressure of the rolls being concentrated on a narrow portion and distributed over a wide portion; and results in an objectionable lack of uniformity in the thickness of such pieces as pointed shoe soles, heel lifts,

and the like; the narrow ends of the shoe soles and a corner of the heel lift, when the latter is fed into the machine otherwise than with its breast parallel to the edge of the knife, being more or less crushed. In the case of pieces varying in hardness, the pressure applied to the rolls is as great upon a soft piece as upon a hard piece, with the obvious result of causing the soft piece, or the soft parts of a piece which varies in hardness, to be compressed. Accordingly, for the reasons above noted, leather splitting machines of the sort commonly used are incapable of splitting all grades of leather, and cut pieces of all shapes and sizes, with exact uniformity and accuracy.

My invention consists in a means for overcoming the defect above noted in splitting machines of the type indicated, by which the pressure applied to the piece by the feed rolls is controlled and varied by the resistance by the piece to penetration by the knife, and therefore to the hardness and width of the piece, so that the unit pressure is approximately the same on wide and narrow pieces or parts of the same piece, and is substantially uniform for soft and hard pieces or parts.

In connection with the invention above stated, I provide guides for the feed rolls of the machine which are so inclined to the direction of feeding that in any adjustment or position of either roll, the clearance between the roll and the knife will be the minimum at the edge of the knife, or in other words that there will be sufficient clearance between the feed rolls, in any adjustment, and any part of the knife to permit the piece operated upon, and the skiving cut from the piece to pass without binding.

I will explain the principles of the invention in connection with the particular machine in which I have embodied the invention, such machine being illustrated in the accompanying drawings.

In the drawings, Figure 1 is a front elevation of the machine. Fig. 2 is a plan view of the machine. Fig. 3 is a cross section on line 3—3 of Fig. 1. Fig. 4 is an end elevation as seen from the left of Fig. 1.

The same reference characters indicate the same parts in all the figures.

The framing of the machine comprises a base 10 and two upright side frames 11 and

12, which provide bearings for the shafts and other moving parts of the machine. These side frames are connected together by a tie rod 13 and are rigidly mounted on the base in the manner shown in the drawings or in any other desired way. At the rear of the machine frame is a transverse beam 14 which supports the splitting knife 15, the knife being provided with slots 16 through which pass holding bolts 17, the latter passing also through a part of the beam 14 and having nuts 18 by which the knife may be clamped to the beam. The forward edge of the knife is beveled equally on opposite sides to a cutting edge 19.

Cooperating feed rolls 20 and 21 are mounted above and below the knife edge, the roll 20 having journals at its ends contained in sliding bearings 22 and 23 adapted to slide in guides 24 and 25 in the frames 11 and 12, respectively, and the roll 21 being similarly mounted in bearing slides 26 and 27, likewise slidingly mounted upon guides 28 and 29 in the side frames 11 and 12, respectively.

The roll 20 is supported against the pressure of the leather pieces operated on in a rigid yet adjustable manner by means of screws and nuts, each of the bearing slides 30 carrying a screw 30 which is threaded into a nut 31 rotatably mounted in the adjacent side frame with its axis in the line of movement of the slide. Each nut carries a worm wheel 32, and the two worm wheels may be 35 adjusted in unison by a shaft 33 which carries a hand wheel 34 for manual operation and on which are mounted worms 34^a and 35 meshing with the worm wheels. This mechanism is merely one old form of adjusting device, which is not part of my invention and which I do not claim. Any other mode of adjusting and holding the rigidly supported roll 20 may be employed without departure from the real invention.

The yielding roll 21 is supported by springs 36, one such spring being mounted under each of the bearing slides and surrounding a rod 37 which is mounted in the slide and extends therefrom through a guide 38 in the side frame. The spring abuts against the end of the guide 38. These springs are of just sufficient power to sustain the weight of the roll and its sliding bearings, but not sufficiently powerful to apply any appreciable pressure to the work. If the roll and bearing slides had no weight, the springs 36 would be unnecessary. The fact that the springs apply no pressure to the work is an important point and should be borne in mind in order that the real invention may be understood.

The feed rolls are preferably mounted with their axes parallel to one another and to the edge of the knife as usual, and adapted to come into contact with one an-

other with their tangent line as near as possible to the edge of the knife.

The rolls are driven by the following mechanism. A shaft 39 on which are mounted the usual fast and loose pulleys 40, 41 turns in bearings in the side frames and carries pinions 42, 43 rigidly fixed near its opposite ends. These pinions mesh with gears 44, 45, respectively, which are mounted on studs projecting outwardly from the side frame. Connected with the gears are wide faced pinions 46, 47, respectively, in mesh with pinions 48, 49, respectively, on the ends of the feed roll 21, or of the shaft on which said feed roll is secured, and these last-named pinions drive the upper roll through a gear train at each end of the machine consisting of pinions 50, 51, and 52, the latter being secured to the upper feed roll and the pinions 50 and 51 being mounted on fixed studs projecting from the adjacent side frame. The gear trains between the shaft 39 and the upper feed roll are duplicated at each end of the machine in order that the forces acting on the rolls may be equal on both ends thereof.

In using the machine, the leather pieces are fed between the rolls 20 and 21 from the front of the machine, this being the right hand side with respect to Figs. 3 and 4. I have provided a guard in front of the rolls, such guard being a plate 52^a having a slit 53 through which the pieces are passed, and provided with lugs 54 at its ends connected with the adjacent side frames by pivot pins 55, but this guard may be omitted without affecting the invention. When the work first passes between the rolls it is engaged but not gripped with any appreciable force, because the springs 36 are so readily yielding. The lower roll yields downwardly by the amount which the thickness of the piece exceeds the distance between the upper roll and the edge of the knife, this excess representing the thickness of the skiving which is to be split from the piece. The upper roll, of course, is adjusted to the thickness which is to be given to the work. When the work encounters the knife and is resisted in its travel thereby, the rotation of the upper feed roll is accordingly resisted owing to its frictional engagement with the work. The power for turning this feed roll is transmitted from the drive shaft through the pinions 48 and 49 on the lower feed roll, and any variation in the resistance to this transmission of motion causes a shifting in position of these pinions and of the roll, since the freedom of movement of the sliding bearings for the roll makes these pinions practically floating pinions. The direction of rotation of the gear, as indicated by the arrows in Figs. 3 and 4, is such that the rotative impulse is applied to the roll 21 upwardly, that is, toward the opposed

rigidly mounted roll 20 and toward the work, whereby the lower roll is caused to apply an increased pressure to the work. This increase in pressure continues as long 5 as the resistance to movement of the work increases, becomes stationary while the resistance continues uniform, and diminishes when the resistance diminishes. As the resistance opposed by the knife varies proportionately to the width of the piece and its 10 hardness, it will be seen that the pressure applied by the floating feed roll varies proportionately to the same characteristics of the work.

15 It is in this feature of the machine that the main feature of the invention consists, that is, in the provision of a driving train for rotating the feed rolls in which the power for rotating the fixed feed roll is transmitted 20 through a floating feed roll in such a way that an increase in the resistance to movement of the rotation of the fixed roll causes the floating roll to be pressed toward the fixed roll with pressure more or less closely 25 proportional to the resistance of the fixed roll. More broadly stated this feature of the invention consists in the provision of means automatically operative to press one 30 of the feed rolls toward the other with a force generally proportional to the resistance offered by the material to being penetrated by the knife.

In this discussion and in the following claims, where the term "fixed" is used in 35 description of the feed roll 20, it is to be understood, of course, that this term is used in a relative sense and is not intended to imply entire absence of mobility of the roll 20, but simply that it is unyielding relatively 40 to the movable or yielding or floating roll 21.

I wish to state further that I do not limit this aspect of the invention to a machine constructed and organized in all respects as here illustrated.

45 Anticipating that the essential principle of the invention embodied in the apparatus here described may be applied in various ways in machines varying widely in appearance and arrangement of parts from this 50 machine, I intend to embrace within the scope of the claims any machine having co-operating rolls, for whatever purpose organized, of which the function and mode of 55 operation are essentially the same as herein described.

Attention is called to the fact that the guideways 25 and 29 by which the displacements of the rolls are guided are inclined to each other and inclined with respect to the 60 central plane of the knife, and also that the guides are straight. These inclinations are such that each roll moves in a straight line approximately perpendicular to the bevel of the nearest side of the knife, so that in any 65 position of either roll the edge is the part

of the knife which is nearest to any point in the surface of the roll. Thus when either roll is adjusted or displaced so as to leave a wide space between itself and the edge of the knife, the distance between the roll and 70 any point on the knife is back from its edge greater than the distance in a straight line perpendicular to the bevel of the knife, from the knife edge to the roll, and thereby in any of these positions sufficient clearance is given to permit free passage of the divided parts of the piece between the rolls and the knife. In machines where the rolls are displaceable perpendicularly to the plane 75 of the knife, and therefore at an acute angle to the bevel of the knife edge, it happens in some of the roll adjustments that the space between the knife edge and roll is wider than that between some point of the knife back of its edge and some other point of the 80 roll, wherefore the passage for the leather after leaving the knife edge is restricted and the stock can not be fed freely.

What I claim and desire to secure by Letters Patent is:

90 1. A leather splitting machine comprising the combination of a splitting knife, complementary feed rolls adapted to grip between them and feed toward the knife the material to be cut, one of said rolls being relatively fixed and the other being movable toward and away from said fixed roll, and pressure applying means constructed and arranged to force the movable roll toward the fixed roll with a pressure approximately proportional 95 to the resistance of the material to being entered by the knife.

100 2. The combination of complementary feed rolls adapted to admit and grip between them the material being fed, one of said rolls being relatively fixed and the other being relatively movable toward and away from said fixed roll, a driving shaft and a gear train driven thereby for applying rotating power to the fixed roll, said gear 105 train including a gear connected with the movable roll and another gear meshing therewith and rotating in a direction tending to force the movable roll toward the fixed roll, whereby variation in the resistance to rotation of the fixed roll causes a 110 variation in the force with which the movable roll is pressed toward the fixed roll.

115 3. In a feed roll mechanism, the combination of coöperating rolls, one of which is movable toward and away from the other, a gear element connected with the movable roll, a driving gear meshing with said element and normally rotating in a direction such as to exert force on said element in a 120 direction toward the fixed roll, and a power transmitting gear train from the movable roll to the fixed roll.

125 4. The combination in a leather splitting machine of a splitting knife, feed rolls ar-

ranged on opposite sides of the knife edge, one of said rolls being relatively unyielding and the other being freely movable toward and away from the first roll, and 5 means for positively rotating said rolls in unison, said means being arranged to force the movable roll toward the unyielding roll with a force proportional to the resistance to feeding of the work acted upon.

10 5. In a feed mechanism, a relatively fixed feed roll, a complementary feed roll mounted to freely move toward and away from the fixed feed roll and a driving gear train for

rotating said fixed roll, said train including 15 a gear on the movable roll and a driving gear in mesh with said gear and arranged at one side of the plane containing the axes of the rolls, the said gear on the movable roll being arranged to drive said gear train.

In testimony whereof I have affixed my 20 signature, in presence of two witnesses.

HARRY LYON.
